UNITED STATES PATENT OFFICE.

EMILE BERLINER, OF BOSTON, MASSACHUSETTS.

HARMONIC TELEGRAPH.

SPECIFICATION forming part of Letters Patent No. 258,356, dated May 28, 1882.

Application filed March 4, 1882. (No model.)

To all whom it may concern:

Be it known that I, EMILE BERLINER, of Boston, in the county of Suffolk and State of Massachusetts, have invented certain Improvements in Harmonic Telegraphs, of which the following is a specification.

The invention is applicable in all systems of telegraphing in which series of waves corresponding to the pendulous vibrations of several reeds are sent over a line, which appear at the receiving-stations either as recognizable tones or in the form of synchronous motions of slow-moving reeds or pendulums. Such systems comprise the so-called "harmonic telegraphs," and they comprise two subsystems, viz: the pulsatory and the undulatory. In the former vibrating reeds or diaphragms close a battery-circuit at each vibration, thereby producing electrical pulsations in the line. In the latter these reeds or diaphragms vibrate in front of coils and magnets and produce electric undulations in the line. If several series of pulsations or undulations are sent simultaneously, they are capable of being analyzed at the receiving-station, so that each series affects one certain receiving-instrument only or particularly. Such receiving-instruments may be reeds or diaphragm-resonators, vibrated by electro-magnets, through which the line passes.

My present application refers to a simple mechanical device for sending undulations; and it consists essentially of a shaft worked by machinery and several current-producing wheels moved simultaneously by said shaft.

In the drawings, Figure 1 shows the shaft as applied to the undulatory system, and Fig. 2 shows a wheel, magnet, and coil separately and detached from the rest.

In Fig. 1, C, C', and C² are current-producing wheels upon the revolving shaft A, moved by the power e. These wheels are of iron or steel, and revolve before the magnets h h h, provided with coils g g' g². When not in use these coils are short-circuited through the keys K K' K²; but the line touches each of the circuits and the key K is grounded at E.

Fig. 2 shows in section a current-producing

iron wheel, C', provided with teeth i i, and revolving before magnet h' and coil g'. Each of the wheels belonging to one system has a number of teeth different from the others of the same system. Hence, by revolving the shaft A, and thereby the wheels C C' C², and depressing, as is shown, with the key K, also the keys K' and K², three distinct series of electric undulations, each at a rate per minute different from the others, will pass into the line L. At the end of the respective lines these electric series of waves can be analyzed by means of forks, reeds, or resonators, as well known to those understanding harmonic-telegraph systems.

It is of course necessary that the shaft A should revolve uniformly and with the same velocity at all times, and, furthermore, that for each wheel representing a series of electric waves an analyzing fork, reed, or resonator should exist at the receiving-station which is particularly affected by the said series of waves. If, now, the Morse keys are used simultaneously by operators, each operator upon depressing his key sends a certain series of waves to the line, and, though the series of each system pass together over the same line, they separately manifest themselves at the distant station, being analyzed by corresponding reeds, forks, or resonators.

What I claim is—

In a harmonic telegraph, a shaft giving motion simultaneously to several iron or steel wheels placed in a magnetic field in proximity with wire coils, each wheel having teeth different in number in a given segment from the other wheels, and thereby producing electric undulations in each coil at a rate per minute different from the rest, substantially as described.

In testimony whereof I have signed my name to this specification, in the presence of two subscribing witnesses, this 2d day of March, 1882.

EMILE BERLINER.
